UNITED STATES PATENT OFFICE.

ALBERT BLAUVELT, OF NEW YORK, N. Y.

DIFFERENTIAL MECHANISM.

SPECIFICATION forming part of Letters Patent No. 548,350, dated October 22, 1895.

Application filed June 6, 1890. Serial No. 354,455. (No model.)

To all whom it may concern:

Be it known that I, ALBERT BLAUVELT, a citizen of the United States, residing in the city, county, and State of New York, have invented certain new and useful Improvements in Differential Mechanism, of which the following is a specification sufficient to enable others skilled in the art to which the invention appertains to make and use the same.

10 My improvements relate to mechanism for effecting a difference in the relative speed of rotation between two parts revolving together in the same direction around a common axis; and the invention consists, essentially, in the 15 use of a stationary worm, together with a worm-gear and suitable auxiliary gearing interposed between the two rotating parts.

In the accompanying drawings I illustrate means for giving practical effect to my improvements, although I do not wish to confine myself to the identical form and construction of parts shown, since it is obvious that various modifications may be introduced without departing materially from the essential features of my invention.

20 Figure 1 is a sectional elevation of one form of my differential mechanism; Fig. 2, a plan of the same. Fig. 3 is a sectional elevation upon plane of line xx , Fig. 2. Fig. 4 is a 25 sectional elevation of a modified form of the mechanism, and Fig. 5 is a similar view taken at right angles to Fig. 4.

As shown in the accompanying drawings, the apparatus is arranged upon and between 30 a vertical shaft A and a sleeve B, both the shaft A and the sleeve rotating together in the same direction, but at slightly different speeds, this difference in speed being effected by my improved mechanism, as hereinafter 35 set forth.

The mechanism, as shown, is applicable to centrifugal machines in which a conveyer forces the material under treatment through the draining-basket, and in other forms of 40 machinery in which it is desired to have two objects rotate in the same direction around a common axis at different speeds as related to each other.

The shaft A and sleeve B are supported in 45 position by suitable bearings or other well-known means, according to the requirements of the particular use to which the mechanism

is to be applied. For the purpose of illustration the drawings show the sleeve B and shaft A as steadied in position vertically by a bearing C, the secured rigidly to a cross-timber D.

55 The bed-plate G of the differential train of gearing G' is secured to the upper extremity of the shaft A, while the large gear g of said train is secured to the upper end of the sleeve B. A vertical counter-shaft g' is mounted in the frame G, its lower end carrying the pinion g² and its upper end the beveled gear g³, which latter meshes with a beveled pinion g⁴, attached to one end of a horizontal shaft g⁵, to 60 the other extremity of which a worm-gear g⁶ is secured. The gears g² g³ are counterbalanced by the weight b.

65 The rotation of the shaft A and the sleeve B is effected by any suitable mechanism, power being applied to either one or the other, as may be required, by pulley, gear, or other well-known means. They are coupled together by the differential mechanism, and would rotate together in the same direction 70 and at the same rate of speed were it not for the worm c', which engages with the worm-gear g⁶. This worm c' is suspended upon a rod d, secured to a stationary support in such manner that while it cannot rotate upon its 75 own axis it is free to adapt itself to the motion of the parts below. The worm is steadied by a bracket a, projecting upward from the frame G, and its lower end c² is stepped in the upper end of the shaft A, the worm being held practically rigid and stationary and acting as a fulcrum against which the worm-gear g⁶ acts to effect the differentiation in motion.

80 The engagement of the worm c' with the worm-gear g⁶ affords sufficient resistance to the rotation of the train of gearing, &c., with the shaft A to compel the worm-gear g⁶ to rotate upon its own axis, the worm c' acting as a stationary fulcrum to effect the change in 85 the relative rates of speed between the sleeve B and the shaft A. The large gear g would have no effect on the pinion g² and its connection were it not for the resistance afforded the worm c', since the whole train G', frame 90 G, and all, would otherwise be carried around with the shaft A without effecting an independent movement of the gears composing the train G. The worm c', however, tends to

hold the train against the action of the large gear g , engaging the pinion g^2 , and since both the shafts g' and g^5 are mounted on the frame G , secured to the shaft A , the consequence is 5 that the motion of the said shaft A is accelerated or retarded according to the pitch and direction of the thread upon the worm c' . The train of gearing shown is well suited 10 for giving a gain or loss of one turn to, say, seven hundred of the draining-cylinder.

My reasons for inventing and using a differential gearing such as shown in the drawings are of a purely mechanical sort. By way of illustration take, for instance, its use 15 in connection with centrifugal apparatus. In such case it is necessary (to avoid clogging) to use a conveyer or screw in the centrifugal of not much less than six inches pitch, preferably more. The material being operated 20 on usually requires to remain for several minutes in the machine—say, for example, five minutes. If, therefore, the conveyer-screw revolves within the strainer once a minute it will move the material through six 25 inches per minute and in five minutes two and one-half feet, which is as much as is a convenient depth of strainer for a single machine, and in turn is more than is convenient to allow for the progress of material 30 during one operation in a double or treble centrifugal. The material being operated on is thrown out against the walls of the machine and presses radially against the same with a force depending on the velocity of rotation, 35 which in ordinary work is sufficient to make it difficult to move the material downward along the annular wall of the strainer. In a machine of the ordinary size of sugar-centrifugals a force of at least a thousand pounds 40 would be required to move a mass of material downward within the strainer-cylinder when running at speed.

From the foregoing it will be seen that the motion required to be imparted to the screw 45 within the strainer-cylinder must be slow, in the neighborhood of once a minute, and must be powerful to positively and evenly screw

the material downward and properly feed the machine. The rotative speed of the entire machine is, however, very rapid and may be 50 taken, for example, at two thousand revolutions per minute. Suppose the problem is to derive a motion from a speed of two thousand revolutions per minute and convert it into a positive even, correlative, but slow and powerful movement of one turn per minute. Obviously no speeds derived from disconnected sources of power can be regulated to such fractional nicety. If belts were employed for this purpose it would be necessary to employ 60 two belts, driven exactly at the same speed, and to have a pulley to the shaft carrying the strainer and another to the screw within the same. One of these pulleys could be as large as forty inches in diameter for an extreme; 65 the other would have to be one two-thousandths or one-fiftieth inch less in diameter. As is well known, all belts "creep," and this creep varies with the load on the belt, and amounts to more than one two-thousandths of 70 the speed of a belt when carrying a due load. Therefore the natural irregularity of transmission of speed by belting is an amount exceeding the amount of difference of speeds necessary for our purpose. 75

Additional to the above a wide and continuous belt would be required in any case to transmit the strain due to the slow torsion and heavy resistance of the screw, as hereinbefore set forth. 80

What I claim as my invention, and desire to secure by Letters Patent, is—

In differential mechanism substantially such as designated, the combination of the gear g , frame G , pinion g^2 , shaft g' , miter gear g^3 , pinion g^4 , shaft g^5 , worm wheel g^6 , and the worm c' , said worm being independently supported and held against rotation upon its longitudinal axis substantially in the manner and for the purpose described. 85

ALBERT BLAUVELT.
